UNITED STATES PATENT OFFICE.

FRANZ HOFFMANN, OF VIENNA, AUSTRIA.

TREATMENT OF LIQUIDS SUCH AS MILK WITH RAYS, MORE PARTICULARLY WITH ULTRA-VIOLET RAYS.

Application filed November 28, 1927, Serial No. 236,354, and in Austria October 30, 1926.

It has often been proposed to treat liquids with rays of short wave length. In order to obtain a uniform action of the rays upon the liquid it is necessary to split up the latter into thin layers. This was done for example by allowing the liquid to flow between two glass partitions, such as plates or cylinders, which were more or less permeable with respect to the rays, thus irradiating the liquid through the glass. In such a case however, the portion of the rays absorbed by the glass is lost.

The method and corresponding apparatus described hereinafter make it possible to treat liquids with rays of any kind, for instance with ultra-violet rays, without a portion of the radiation being lost by absorption.

According to the method forming the subject matter of the present invention, the liquid is first of all converted into a thin layer and thereupon led over a very interrupted surface, such as for instance a grid. In such a case it not only flows away over the grid bars, but owing to the surface tension also over the interruptions in the surface, so that it forms a continuous layer (thin film of milk), which is not enclosed by walls, but flows away freely. Layers of liquid constituted in this way can now be treated with rays, without any loss by absorption.

For the purpose of obtaining the full effect of the radiation it is advisable to make the grid in the form of a for instance cylindrical hollow body and to locate the source of the rays in the central axis of the cylinder. The diameter of the hollow body and at the same time the distance of the source of the rays from its inner surface is so chosen that as powerful an action as possible on the liquid is ensured.

The material of which the interrupted surface is made depends in the first place upon the characteristics of the liquid to be treated; for milk, the treatment of which is the chief consideration in this case, use may be made of sheet metal. The means used for generating the rays in the present method is an electric light source, which is rich in ultra-violet rays, such as for instance a lamp of the Farlan-Moore type, i. e. a kind of Geissler tube of pure fused rock crystal, preferably provided with a filling of inert gas and condenser electrodes. The tubes can be operated with high-voltage alternating current of low, medium or high frequency as desired. Instead of this

means for generating the rays use might however also be made for instance of the well-known Uviol lamp. The method and apparatus forming the subject matter of the present invention are however also suitable for other rays than the ultra-violet.

The accompanying drawing illustrates diagrammatically in longitudinal section one constructional form of the apparatus used for carrying out the method in question.

The stand 1 supports by means of the arms 2 and 3 on the one hand a bulb-shaped hollow body 4, and on the other hand a sleeve 5 arranged around the wire grid 14. On the bulb 4 is provided a funnel-shaped supplying trough 6 for the milk, which enters the apparatus through pipe 7 and tap 8. The trough 6 is rigidly connected by the arms 9 and 9' with an annular part 10 and is open at the top and bottom; the diameter of the upper aperture is considerably larger than that of the lower. The annular part 10 embraces the neck of the bulb 4 and can slide up and down on it. Close to its upper edge it is provided outside with a screw-thread, which engages with a corresponding screw-thread on the inner surface of a nut 11. This nut 11 is also slid onto the neck of the bulb 4 and rests there on the projection 12, on which it is freely rotatable. When the nut 11 is turned, the annular part 10 is accordingly lifted or lowered and with it the trough 6 because it is rigidly connected with the annular part 10 by the arms 9, 9'. As the lower aperture of the trough 6 reaches right down to the outer surface of the bulb 4, by the raising of the trough 6 the slit 13 between the lower edge of the trough and the wall of the bulb becomes larger and when the trough is lowered becomes smaller.

The milk enters first into the trough 6, passing from here through the slit 13 to the surface of the bulb 4, becomes distributed over the latter in a thin layer and then flows over the grid 14, bridging over the various meshes of the grid with a thin film of liquid. Inside the grid is located the means 15 generating the rays, the electric current operating the same passing through the hollow neck of the bulb 4 by means of the wires 18, 18'. The treated milk flows into the container 16, from which it finally emerges through 17. In many cases, as for instance in the case of milk, it is undesirable owing to the formation of ozone, to allow air to have free access to the

liquid during the irradiation. For the purpose of preventing the free entry of air, a sleeve 5 which is open at the top and bottom is provided a little distance from the outer surface of the grid. By allowing the sleeve to be immersed under the surface of the milk it is possible to shut off the admission of air from below. It is however also possible to exclude the possibility of the formation of ozone by passing an inert gas into the interior of the sleeve. In order fully to utilize the rays passing through the grid 14, it is advisable to make the sleeve 5 of a material which reflects the rays or to make its inner surface capable of reflecting in a known manner.

The described treatment has numerous effects, in the case of milk, in addition to sterilizing it, its vitamin content is also increased. It is clear that it is possible by means of the invention to treat the liquid in as thin a layer as desired by means of a simple device, while utilizing the energy of the rays to the fullest extent.

25 I claim—

1. Device for irradiating liquids more especially with ultra-violet rays, comprising in combination a hollow body, a grid forming an extension of the latter, a source of light-rays arranged within the said grid, and a vertically adjustable trough, open at its lower

end, surrounding the hollow body, for the purpose specified.

2. Device for irradiating liquids more especially with ultra-violet rays, comprising in combination a hollow bulb-shaped body, a cylindrical grid forming an extension of the latter, a source of light-rays arranged within the said grid, and a vertically adjustable trough, open at its lower end, surrounding the bulb-shaped body, the lower end of said trough being in spaced relation to the hollow bulb-shaped body.

3. Device for irradiating liquids more especially with ultra-violet rays, comprising in combination a hollow bulb-shaped body, a cylindrical grid forming an extension of the latter, a source of light rays arranged within the grid, wires for the supply of electric current passing through the said bulb-shaped body and being connected with the said source of light rays, and a vertically adjustable trough surrounding the bulb-shaped body and open at its lower end, for the purpose specified.

4. A device as claimed in claim 2 further comprising a cylindrical sleeve mounted around the cylindrical grid, for the purpose specified.

In testimony whereof I affix my signature.

FRANZ HOFFMANN.
